PREPARATION OF PHOSPHINIC CHLORIDES BY CHLORINATION OF PHOSPHINOTHIOIC ACIDS WITH ELEMENTAL CHLORINE

Willis G. Craig, Willoughby, Ohio, assignor to The Lubrizol Corporation, Wickliffe, Ohio, a corporation of Ohio

No Drawing. Application January 26, 1954,
Serial No. 406,330

6 Claims. (Cl. 260—543)

This invention relates to a novel method for preparation of acid chlorides. More particularly it relates to a novel method for preparation of certain phosphorus-containing acid chlorides.

Previous methods for preparing acid chlorides have generally involved the utilization of certain well-known reagents, such as phosphorus pentachloride, phosphorus trichloride, thionyl chloride, etc. These reagents, while effective in most cases, are not as efficient as is sometimes desired simply because there is available from the reagent only one or two atoms of chlorine which will appear in the acid chloride product, whereas a relatively large proportion of the reagent molecule, such as sulfur, phosphorus, chlorine, etc. is of no avail and constitutes an economic waste. Nevertheless, the use of these reagents is necessary when, as is generally the case, simpler and less expensive chlorinating reagents will not serve the purpose.

The phosphorus-containing acid chlorides which are produced in the process of this invention are illustrated by the structural formula:

wherein Ar and Ar' are the same or different aromatic radicals, each bound to the phosphorus atom through a benzenoid carbon atom. Such compounds are the phosphinic chlorides.

The availability of phosphinic chlorides in the past has depended principally upon three preparative methods. The one involved oxidation of a monochlorophosphine, usually with air under relatively mild conditions. A second method utilized a trichlorophosphorane as the starting material and this was hydrolyzed in such a manner as to yield the corresponding phosphinic chloride. The third method consisted in treating the phosphinic acid with either thionyl chloride or phosphorus pentachloride.

It is an object of the present invention to provide a process for the preparation of phosphinic chlorides. Another object is to provide such a process which is economical and convenient. Other objects will be apparent from the following description of the invention.

To the accomplishment of the foregoing and related ends, said invention then comprises the features herein-after fully described and particularly pointed out in the claims, the following description setting forth in detail certain illustrative embodiments of the invention, these being indicative, however, of but a few of the various ways in which the principle of the invention may be employed.

Broadly stated, this invention relates to the method for preparing phosphinic chlorides having the formula:

wherein Ar and Ar' are the same or different organic

2

radicals bound to phosphorus through a benzenoid carbon atom, which comprises reacting at least one diorganophosphinothioic (thiophosphinic) acid in which the organo radicals are bound to phosphorus through a benzenoid carbon atom with chlorine.

The process is illustrated by the following equation:

wherein Ar and Ar' are the same or different aromatic radicals, each bound to the phosphorus atom through a benzenoid carbon atom. The aromatic radicals may be either substituted or unsubstituted hydrocarbon radicals, including aryl and alkaryl radicals, and are illustrated by the following specific examples: phenyl, tolyl, xylol, naphthyl, xenyl, chlorophenyl, dichlorophenyl, nitrophenyl, nitronaphthyl, anisyl, amylphenyl, waxphenyl, etc.

The process is particularly convenient and simple in its operation. Chlorine is introduced into the phosphinethioic acid at slightly elevated temperatures, preferably in the presence of an inert solvent. The solvent need only be inert to the action of chlorine under the conditions of the process and suitable solvents include principally the chlorinated hydrocarbons and aromatic hydrocarbons. The process is operable at room temperatures or lower, the reaction being somewhat exothermic, although it is preferred to utilize higher temperatures, up to and in some particular instances above 100° C. Usually the temperature range of 20–80° C. is satisfactory.

The duration of the reaction is usually 1–3 hours. Reactions run at lower temperatures require, of course, a longer time than reactions run at higher temperatures and consequently, it is within the contemplated scope of this invention to carry out the process within the range of time of about 0.5–10 hours.

The aromatic phosphinic chlorides are in general liquids. The lower molecular weight members of this class are susceptible to distillation at diminished pressure and where purification of such a product is indicated, such purification is best accomplished by distillation.

The aromatic phosphinethioic acids which comprise the starting materials in the process of this invention are conveniently available via the alkaline hydrolysis of the corresponding aromatic phosphinethioic chlorides. These acid chlorides are in turn conveniently prepared by the reaction of phosphinodithioic acids with hydrogen chloride, as disclosed in copending application Serial No. 406,326, filed January 26, 1954, and the preparation of the phosphinodithioic acids is effected, as indicated in copending application Serial No. 406,323, filed January 26, 1954, by the reaction of an aromatic compound with phosphorus pentasulfide in the presence of aluminum halide. The overall sequence of reactions involved in an ultimate synthesis of the phosphinic chlorides described herein is as follows:

1. $4\text{ArH} + \text{P}_2\text{S}_5 \xrightarrow{\text{AlCl}_3} 2\text{Ar}_2\text{PSSH} + \text{H}_2\text{S}$
2. $\text{Ar}_2\text{PSSH} + \text{HCl} \longrightarrow \text{Ar}_2\text{PSCI} + \text{H}_2\text{S}$
3. $\text{Ar}_2\text{PSCI} + \text{NaOH} \xrightarrow{\text{H}^+} \text{Ar}_2\text{PSOH} + \text{NaCl}$
4. $\text{Ar}_2\text{PSOH} + \text{Cl}_2 \longrightarrow \text{Ar}_2\text{POCl} + \text{S}_2\text{Cl}_2$

The invention is illustrated in detail by the following examples.

Example 1

To a solution of 200 grams of diphenyl phosphinethioic acid in 250 grams of benzene there was introduced a stream of chlorine over a period of ninety minutes. The temperature rose from 28° C. to 72° C. before receding again to room temperature. Excess chlorine was

3

removed by bubbling dry nitrogen through the mixture. The mixture then was filtered and concentrated by heating to a final temperature of 100° C./3 mm. The residue was distilled to yield 115 grams of a non-viscous liquid, B. P. 167-172° C./0.6 mm. This distillate was substantially pure diphenyl phosphinic chloride.

Example 2

A solution of 108 grams of ditolyl phosphinothioic acid in 200 grams of benzene was treated at room temperature with a stream of chlorine. The temperature of the exothermic reaction was held below 60° C. and after 75 minutes excess chlorine was removed by bubbling nitrogen through the mixture. The mixture was concentrated by heating to a final temperature of 110° C./5 mm. The residue, substantially pure ditolyl phosphinic chloride, showed the following analyses:

	Percent
S	0.9
P	11.5
Cl	14.6

Example 3

A slurry of 406 grams of diphenyl phosphinothioic acid in 400 grams of benzene was treated with chlorine for two hours. Volatile materials were removed by distillation and the residue was distilled to yield 360 grams of light yellow liquid, B. P. 190-200° C./2 mm., which was substantially pure diphenyl phosphinic chloride. The analyses were:

	Percent
S	Trace
P	13.8
Cl	15.0

Example 4

A slurry of 225 grams of diphenyl phosphinothioic acid in carbon tetrachloride was treated with a stream of chlorine until a clear solution resulted. This solution was concentrated by heating at reduced pressure (water aspirator). The residue was distilled to yield a fraction boiling at 169-180° C./0.8-2.3 mm. This fraction was shown to be substantially pure diphenyl phosphinic chloride.

Example 5

Chlorine was bubbled into a slurry of 420 grams of di(chlorophenyl) phosphinothioic acid in 400 grams of benzene for two hours. The temperature during this time ranged from 50-70° C. The mixture was filtered and then concentrated by heating to a final temperature of 100° C./20 mm. The residue was distilled to yield a fraction boiling from 205-224° C./2 mm. The analyses

4

of this fraction, substantially pure di(chlorophenyl) phosphinic chloride, were as follows:

	Percent
S	0.3
P	9.9
Cl	33.8

The phosphinic acid chlorides of this invention may be employed as improving agents in lubricating oils and greases, in asphalt emulsions, insecticidal compositions, as starting materials for preparing phosphorus compounds, fireproofing and stabilizing agents in plasticizers and plastics, paint dryers, rust inhibiting compositions, pesticides, foaming compositions, cutting oils, metal drawing compositions, tanning assistants, metal cleaning compositions, penetrating agents, gum solvent compositions, fat splitting agents, flotation agents, and improving agents for hydrocarbon fuels, etc.

Other modes of applying the principle of the invention may be employed, change being made as regards the details described, provided the features stated in any of the following claims, or the equivalent of such, be employed.

I therefore particularly point out and distinctly claim as my invention:

- 25 1. The method for preparing phosphinic chlorides having the formula:

30 wherein Ar and Ar' are non-functional aromatic radicals bound to phosphorus through a benzenoid carbon atom, which comprises reacting a phosphinothioic acid of the following structure

35 wherein Ar and Ar' are non-functional aromatic radicals bound to phosphorus through a benzenoid carbon atom, with chlorine.

40 2. The method of claim 1 characterized further in that the aromatic radicals are aromatic hydrocarbon radicals.

45 3. The method of claim 1 characterized further in that the aromatic radicals are chloro-aromatic radicals.

4. The method of claim 1 characterized further in that the aromatic radicals are phenyl radicals.

5. The method of claim 1 characterized further in that the aromatic radicals are tolyl radicals.

50 6. The method of claim 1 characterized further in that the aromatic radicals are chlorophenyl radicals.
